UNITED STATES PATENT OFFICE.

ANDREW BERGSTROM, OF CHICAGO, ILLINOIS.

TOOL-HOLDER.

993,335.

Specification of Letters Patent. Patented May 30, 1911.

Application filed October 10, 1910. Serial No. 586,318.

To all whom it may concern:

Be it known that I, ANDREW BERGSTROM, a citizen of the United States, and a resident of the city of Chicago, county of Cook, and

5 State of Illinois, have invented certain new and useful Improvements in Tool-Holders, of which the following is a specification.

My invention relates to improvements in tool-holders and has for its object the production of a simple and efficient device of this character for holding edged tools in contact with a grind stone when sharpening the same.

10 A further object is to provide a tool-holder, the construction of which is such that the operator may press the cutting edge of the tool against the grind stone with one hand and with the other hand rotate said stone to effect the sharpening of the tool.

20 A further object is to provide means for varying the angle of the cutting edge of the tool being ground.

Other objects will appear hereinafter.

With these objects in view my invention 25 consists in the novel construction and the arrangements of parts as will be hereinafter more fully described and particularly pointed out in the appended claims.

My invention will be best understood by 30 reference to the accompanying drawings forming a part of this specification, and in which—

Figure 1 is a side elevation of my invention in its preferred form, Fig. 2 is a top 35 plan view thereof, and Fig. 3 is a transverse section taken on line $x-x$ of Fig. 2.

The preferred construction for carrying my invention into effect as illustrated in the accompanying drawings comprises a frame 40 1 having bearings 2 mounted thereon, said bearings supporting a shaft 3 carrying a grind stone 3'. An operating handle 4 is provided on the shaft 3, which handle is adapted to be grasped by the right hand of 45 the operator. An ordinary water tank 5 is provided for the grind stone 3' in order that the latter may be constantly supplied with water. The frame 1 comprises transverse members 6 which have lateral extensions or 50 projections 7, thumb-clamping screws 8 being provided in the uppermost of these extensions. Thus the frame carrying the grind stone may be detachably secured to a table, bench or the like. When the frame is attached to a table 9 as shown in Figs. 1 and 55 2 the crank 4 may be easily turned by the

right hand of the operator, it being necessary to manipulate the tool-holder with the left hand as will be hereinafter described.

60 The tool-holder comprises a transverse member 10 which is detachably and adjustably secured to the frame 1 by means of bolts 11 and thumb nuts 11' therefor, longitudinal slots 12 being provided in order that said bolts may be longitudinally adjusted. Extending upwardly from the central portion of the transverse member 10 is an upright inverted U-shaped member 13, formed from a metallic strip the ends of 70 which are secured together by a rivet 14. The member 13 is secured to the transverse member 10 by means of a detachable bolt 15 as clearly illustrated in Figs. 1 and 2. In order that the member 13 may be moved to a position on the member 10 nearer the grind stone 3' than that shown in the drawings, a supplementary bolt-hole 16 is provided in said member, said bolt-hole being adapted to receive the bolts 15. The front portion of 75 the member 13 is provided with a series of perforations 17 which are designed to receive a reduced extremity 18 of the handle extension 19. It is apparent that the angle of the cutting edge of the tool may be varied 80 to suit the operator by using any one of the perforations 17.

85 The forward end 20 of the handle extension 19 is enlarged and is provided with a tool-receiving recess 21. The tool 22 is interposed between the recess 21 and the rear extremity 23 of the handle as clearly indicated in Fig. 1. The tool 22 is held securely 90 in position by means of a thumb screw 24 which engages the top face of the tool. 95 Screws 25 are provided for securing the rear extremity of the operating handle 26 to the enlarged portion 20 of the handle extension 19. The forward end of the handle 26 is curved downwardly as shown in Fig. 1 in 100 order that the operator may readily control the same in grinding the tool. If it is desired to make the angle of the cutting edge of the tool 22 more acute, the extremity 18 105 is engaged with a perforation 17 near the top of the member 13 and if it is a tool having considerable length the member 10 is secured to the rear of the frame 1.

A grind stone and tool-holder of the construction set forth is convenient in use and 110 efficient in operation.

While I have shown what I deem to be

the preferable form of my invention I do not wish to be limited thereto as there might be various changes made in the arrangements of parts and details of construction 5 without departing from the spirit of my invention and hence I desire to avail myself of such variations and modifications as are comprehended within the scope of the appended claims.

10 Having described my invention what I claim as new and desire to secure by Letters Patent is:

15 1. A device of the class described comprising a frame; a standard formed of a metallic strip bent into substantially uniformed U-shape with its end bent to overlap and riveted together, the forward limb of said member being arranged substantially vertical and perforated; an operating handle; 20 an extension secured to said handle and adapted to be inserted in any of the perforations of said standard; and a tool clamp provided on said handle, substantially as described.

25 2. A device of the class described, comprising a frame; a standard formed of a metallic strip bent into substantially uniformed U-shape with its ends bent to overlap and riveted together, the forward limb 30 of said member being arranged substan-

tially vertical and perforated; a member adjustably mounted on said frame and to which said standard is secured; an operating handle; an extension secured to said handle and adapted to engage one of the perforations of said standard; and a tool clamp provided on said handle, substantially as described.

35 3. In a device of the class described, a frame; a transverse member adjacent and 40 adjustably secured to said frame; a standard formed of a metallic strip bent into substantially uniformed U-shape with its ends bent to overlap and riveted together, the forward end of said member being arranged substantially vertical and perforated, said standard being secured to said transverse member; an operating handle and an extension therefor bolted thereto, said extension having a reduced rear extremity adapted to 45 engage in any of the perforations of said vertical limb and to clamping means in said operating handle, substantially as described.

50 In testimony whereof I have signed my name to this specification in the presence of 55 two subscribing witnesses.

ANDREW BERGSTROM.
